UNITED STATES PATENT OFFICE

2,628,121

BUCKET

William M. Wood, Jonesville, Va.

Application May 26, 1950, Serial No. 164,430

1 Claim. (Cl. 294—53.5)

1

The present invention relates to a bucket and it consists in the combinations, constructions and arrangements of parts hereinafter described and claimed.

Generally there is provided a bucket which, while capable of many other uses, is particularly adapted for use as a tool for cleaning out post and pole holes particularly where mud and water have accumulated in such holes. The device consists essentially of a bucket having a round bottom and substantially cylindrical sides. The top of the side walls have formed therein a lip and a portion of the bottom adjacent such lip is formed in an upwardly sloping plane. A yoke hingedly connects the sides of the bucket at either side of the lip portion thereof and an elongated handle is centrally affixed to the yoke. A second elongated handle is hingedly connected to the lower end of the bucket at that side thereof remote from the portion thereof forming the lip. Manipulation of the two handles permits the tilting of the bucket to fill the same and/or to use it as a scoop while further manipulation of the handles will return it to its normal position whereupon the bucket and its contents may be lifted by the handles to the surface of the ground or other place convenient for the disposal of such contents.

It is accordingly an object of the invention to provide a device of the character set forth which is simple in construction, inexpensive to manufacture and yet efficient and effective in use.

Another object of the invention is to provide a device of the character set forth which is particularly adaptable to removing liquids and the like from rounded holes in the ground.

A further object of the invention is to provide, in a device of the character set forth, novel means for manually manipulating a bucket forming a part of the invention at a point remote from such bucket.

Other and further objects of the invention will become apparent from a reading of the following specification taken in conjunction with the drawing, in which:

Figure 1 is a fragmentary side elevational view of an embodiment of the invention with a bucket forming a part of such invention in a position ready to be used as a scoop.

Figure 2 is a view similar to Figure 1 but showing the bucket moved forwardly from its position as shown in Figure 1.

Figure 3 is a view similar to those shown in Figures 1 and 2 but showing the bucket in a normal or carrying position.

2

Figure 4 is a perspective view of Figure 2 taken from the front side thereof, and

Figure 5 is an enlarged fragmentary sectional view taken along line 5—5 of Figure 2.

5 Referring more particularly to the drawing, there is shown therein a bucket generally designated at 10 and having a circular bottom and substantially cylindrical sides 12.

Regarding for the purposes of description the 10 normal position of the bucket 10 to be that shown in Figure 3 where the bottom 11 is shown in a horizontal position, the forward upper portion of the walls 12 is integrally formed into an upwardly extending lip 13 and a segmental portion 15 of the bottom 11 extends forwardly and upwardly from the main bottom portion 11 to join that part of the walls 12 immediately below the lip 13.

The bucket 10 is provided with a pair of 20 diametrically opposed outwardly extending ears 15 one at either side thereof adjacent the upper end of the walls 12 and to each is pivotally connected the lower end of a yoke member 16 whose upper ends are affixed to opposite sides of an elongated main handle 17 by means of rivets 18 or the like.

Adjacent the lower rear end of the bucket 10 there is provided an outwardly extending bracket 19 through which extends a strap 20 whose ends 30 are fastened to the lower end of an elongated tilting handle 21 by means of rivets 22 or the like.

In operation, it will be apparent that the device may be utilized for a variety of work but 35 that it is particularly useful in removing mud and water from post and pole holes and that with regard to the latter for example, it may first be lowered into such hole in its position as shown in Figure 1 wherein the tilting handle 21 has been 40 lifted relatively to the main handle 17, it being understood, of course, that to accomplish this result the handle 17 may have actually been lowered while the handle 21 remained stationary or that, again, some motion may have been imparted to both of the handles to manipulate the bucket 10 into the position referred to wherein the lip 13 may directly engage the bottom of the hole.

The next operation is the forward movement 50 of the lip 13 by moving the handle 17 upwardly with respect to the handle 21 always bearing in mind the explanation given with respect to such relative movements in the paragraph next hereinabove. Continuing this movement in the same 55 manner will eventually bring the bucket 10 to

the position shown in Figure 3, that is to say to a "carrying" position with the bottom 11 in a horizontal position and the sides 12 in a vertical position. During these actions, it will be apparent that the segmental portion 14 of the bottom of the bucket will allow a normal downflow of material scooped by the lip 13 to flow into the interior of the bucket without impairment which might otherwise be the case if the entire bottom was flat.

While but one form of the invention has been shown and described herein, it will be readily apparent to those skilled in the art that many minor forms of the invention may be made without departing from the spirit of the invention or the scope of the appended claim.

What is claimed is:

A device of the character described comprising a bucket having substantially cylindrical sides and a circular bottom, a yoke centrally and pivotally affixed to the sides, an elongated handle affixed centrally to said yoke, an upwardly ex-

tending lip formed integrally with the forward side of said bucket, and an elongated handle pivotally connected to the lower rearward end of said bucket, said bottom having a segmental portion at the forward side thereof having an upwardly and outwardly extending plane substantially parallel with said lip.

WILLIAM M. WOOD.
